ANTENNA COUPLING DEVICE

Edward L. Minnich, Carlisle, Pa., assignor, by mesne assignments, to Dynamics Corporation of America, New York, N.Y., a corporation of New York

Application January 25, 1955, Serial No. 483,948

4 Claims. (Cl. 343—851)

This invention relates to improved antenna coupling arrangements which are particularly advantageous for coupling the output power of a transmitter to the antenna used to radiate the transmitted signal. These coupling devices are also used to advantage for signal reception and are well suited for transmission and reception using the same antenna in accordance with well known duplexing arrangements.

With the radio communications traffic of all the allocated service bands steadily increasing, the problem of interference between the various transmissions becomes more acute. As the available spectrum is fixed and the allocation of bands within fixed limits has been made on a quasi-permanent basis by the Federal Communications Commission, the only alternative which can be resorted to when additional interference cannot be tolerated is the imposition of more stringent requirements for each transmission in a particular band. These limitations require that spurious radiations from the radio equipment be reduced to a very low level. In particular, in private radiotelephone service such as, for example, the marine radio telephone band, the reduction of harmonic radiations to a greater degree than heretofore attained is desirable.

It is the principle object of the present invention to provide in radio communication apparatus improved antenna coupling arrangements.

Another object is to provide antenna coupling arrangements having extended attenuation of harmonic frequencies.

A further object is to provide improved antenna coupling arrangements which provide convenient adjustment for obtaining optimum performance under all conditions of operation.

Another object is to provide the foregoing coupling arrangements which are simple and economical in construction and completely reliable in operation while achieving the extended performance characteristics heretofore described.

These and other objects are obtained in the present invention by coupling between the tuned circuit of the radio apparatus and the antenna with a spiral coil coupled to the helical coil of the tuned circuit with an interposed Faraday shield. Spiral progressive taps on the spiral coupling coil in combination with switch tap connection to an antenna loading coil are provided for different operating conditions.

In the drawings:

Fig. 1 is a partially schematic view of an antenna coupling system showing a side elevation of the coupled coils of the system;

Fig. 2 is a front elevation of the spiral coil and shield according to the invention; and

Fig. 3 is a partial section view along the line 3—3 of Fig. 2.

Referring to Fig. 1 the system is shown having a conventional antenna 4 for the transmission or reception or both of radio signals and is connected to a loading coil

2

5. The loading coil 5 has connections at a series of taps 6 which are individually selected by a switch contact 7 for connection with either of two leads 8 and 9. The leads 8 and 9, respectively, terminate in spring clip connectors 10 and 11.

The antenna 4 transduces energy for a radio circuit 14 which has associated therewith a parallel resonant circuit in which the inductance includes a helical coil 15. The radio circuit 14 may be a transmitter, a receiver or any 10 of the transceiver arrangements for which the antenna 4 will function to transmit or receive energy as required. As an important application of the present invention relates to transmitters, the subsequent description will be made for the circuit 14 as a radio transmitter with the 15 coil 15 being the resonant inductance in the power output circuit thereof.

The coil 15 is connected in circuit by capacitor 16 and is directly grounded at the opposite end to a chassis terminal 17. The terminal 17 may be integrally formed with 20 a metallic chassis 18 which also serves as support and shield for the coil 15.

Mounted to the chassis 18 is an assembly comprising 25 separate plates 19 and 20 of insulating material which may be secured together by any suitable means. The plate 19 is adjacent the gorundend end of the coil 15. On the face of the plate 19 which is adjacent the coil 15 is supported a Faraday shield structure 21 which preferably comprises a grid of parallel wires imbedded in the surface of plate 19 and connected at their lower ends to 30 a common bus 22. On the opposite face of the plate 19 is supported a spiral coil 23 which may be imbedded in the surface of plate 19 but out of contact with the shield 21. Instead of the spiral coil 23, a series of connected concentric circles may be employed but in either 35 case the various convolutions thereof lie in the same plane in close proximity to the Faraday shield 21 which in turn is in close proximity to the helix coil 15.

The coil is provided with a series of taps which may be 40 formed as loops 24 projected at right angles to the plane of the coil 23. The loops 24 project through appropriately spaced holes in the plate 20. One end of the spiral coil 23 and the common bus 22 of the shield 21 are connected to ground at the lug 17. The spring clip connectors 10 and 11 are arranged for connection to 45 selected ones of the projecting loops 24.

In Fig. 2 the shield 21 and spiral coil 23 are shown 50 as they appear behind plates 19 and 20 of transparent insulating material. Projecting through the plate 20 are the loops 24 with one loop tap being provided in each 55 turn of the spiral 23. The position of the loops or taps 24 progresses for each turn with the result that adjacent loops 24 connect approximately a single turn of the spiral wound coil 23. Behind the coil 23 on the back face of the plate 19 is the shield 23 having a plurality of parallel conductors 30 extending beyond the area covered by the coil 23.

Fig. 3 shows the arrangement of the plates 19 and 20 and the preferred imbedded position for the conductor 30 of the shield 21 and the coil 23.

60 It is to be understood that printed circuits or etched plate techniques lend themselves admirably to this invention. The Faraday shield 21 can in most all if not all applications be laid down on a sheet of insulating material with the spiral coil 23 embedded in or attached 65 to the opposite face. In applications where the level of power to be handled in the low spiral coil is low, printed circuitry techniques can be similarly employed with the set of tap connections 24 riveted, soldered, or otherwise suitably attached thereto.

70 The operation of the present invention as used in a radio telephone transmitter, for example, the marine radio band has resulted in highly satisfactory perform-

ance together with an improvement of approximately 10 db attenuation of second harmonic radiation. Operation in the upper half of the band is effected with switch 7 in position to connect lead 8 to one of the taps 6 on loading coil 5. In similar manner operation on the lower half of the band obtains with switch 7 connecting loading coil taps 6 to lead 9. Coupling adjustments in the different band switch positions are made by means of respective clips 10 and 11.

Many variations of the disclosed embodiment will be apparent to those skilled in the art in the light of the present teaching and are to be considered within the scope of the invention as defined in the appended claims.

I claim:

1. A radio transmitting coupling system comprising a radiating antenna, a loading coil for said antenna having a plurality of sets of tap connections, separate leads for connection to respective sets, switch means for selectively connecting said leads to said sets and providing for each lead so connected selective connection to the taps of the respective set, a transmitter tuned power output circuit including a helical coil having one end grounded, said helical coil having a longitudinal axis and a base substantially perpendicular to said axis, a flat spiral coil having a plurality of turns with tap connections to individual ones of said turns, means for mounting said spiral coil parallel to said base of said helical coil at said grounded end and centered on said axis, a ground connection for said spiral coil, a grounded Faraday shield parallel to said spiral coil and mounted between said spiral coil and said base, and means for selectively connecting said leads to individual taps on said spiral coil.

2. Apparatus according to claim 1 in which said spiral coil is formed on one surface of a flat dielectric sheet,

5 said Faraday shield is formed on the other surface of said sheet, and a second flat dielectric sheet having holes therein is secured over said spiral coil with said holes in registry with said taps and said tap connections projecting through said holes.

3. A radio signal coupling system comprising an antenna, a loading coil for said antenna, a tuned circuit having a helical coil with a flat base, a flat spiral coil having a plurality of turns with tap connections to individual ones of said turns, means for mounting said spiral coil parallel to said base of said helical coil and centered on the axis thereof, a Faraday shield mounted parallel to said spiral coil and between said spiral coil and said base, and circuit means for selectively connecting said antenna to said tap connections.

4. In an antenna circuit for coupling to a helical coil with a flat base, a flat spiral coil having a plurality of turns with tap connections to individual ones of said turns, a flat dielectric plate supporting said spiral coil on one surface thereof, a Faraday shield mounted on the other surface of said plate, means for mounting said plate parallel to said base of said helical coil with said shield between said coils, and connections to said taps for placing an antenna in circuit with said spiral coil.
